1,675,291

UNITED STATES PATENT OFFICE.

VINCENT BENDIX, OF CHICAGO, ILLINOIS, ASSIGNOR TO BENDIX BRAKE COMPANY, OF CHICAGO, ILLINOIS, A CORPORATION OF ILLINOIS.

BRAKE SHOE.

Application filed March 28, 1927. Serial No. 178,878.

This invention relates to brakes, and is illustrated as embodied in an auxiliary shoe for a three-shoe internal expanding automobile brake. An object of the invention is to provide a very light shoe, by forming it of a single-thickness web secured to an outer band carrying the lining, this light type of construction being made feasible by reinforcing the part of the web which projects at the end of the shoe as an integral pivot arm, this being the point at which the greatest crushing or buckling strain comes when the brake is applied.

Preferably the reinforcement is in the form of a separate plate or the like secured to the side of the arm, or a pair of such plates secured to opposite sides of the arm. It will be seen that by thus reinforcing this particular part of the shoe, excess weight in all the rest of the shoe is avoided, and a very light but adequately-strong shoe is formed.

The above and other objects and features of the invention, including various novel and desirable details of construction, will be apparent from the following description of one illustrative embodiment shown in the accompanying drawing, in which:

Figure 1 is a side elevation of the shoe;

Figure 2 is a cross-section through the shoe, on the line 2—2 of Figure 1;

Figure 3 is a cross-section through the shoe on the line 3—3 of Figure 1, showing the reinforcing plates;

Figure 4 is a section through the shoe on the line 4—4 of Figure 1, showing the bushing at the end of the shoe which receives the pivot or anchor for the shoe;

Figure 5 is a partial section through the shoe on the line 5—5 of Figure 1, showing the mounting for the cam-engaging thrust rollers; and

Figure 6 is an inside elevation of the lower end of the shoe, looking in the direction of the arrows 6—6 of Figure 1.

The shoe selected for illustration is the auxiliary shoe of a brake of the general type of that fully described in Patent No. 1,628,388, granted Bendix Brake Company on May 10, 1927, on an application filed by John R. Cautley. It includes generally an outer band or rim 10, to which the brake lining (not shown) may be riveted, and which may have short stiffening flanges 12 at its edges, and a separate member 14, forming a central stiffening web and arc-welded

along its outer edge to the inner face of band 10.

Web 14 is shown formed with an opening 16 for the anchor of an adjacent shoe, as explained in the above-identified Cautley patent, and is of greater width at this point so that it has the same total strength in spite of the opening; it is also shown with an opening 18 for the attachment of a return spring and with an opening 20 for a steady rest. At the upper end of the shoe, web 14 is strengthened by a pair of plates or stampings 22 spot-welded to its sides, and is provided with cam-engaging rollers 24 mounted on a pivot 26.

The present invention relates to the use of a light construction of this general character, whether or not including all of the features described above, in a shoe for a heavy brake, by providing a very strong but light pivot or anchor arm at the end of the shoe, formed by reinforcing an integral extension 28 of the web 14. The extension 28 is provided at its extreme end with a bushing 30 for the pivot or anchor.

I prefer to reinforce the outer edge of extension 28 by continuing band 10 as a narrowed extension 32 arc-welded or otherwise secured to extension 28, and formed nearly to the end of the shoe with integral wings 34 or flanges 34 bent into engagement with the sides of the extension 28 and, if desired, arc-welded thereto.

The body of extension 28, which is under a heavy buckling strain when the brake is applied, is reinforced by one or more plates 36, two being shown, spot-welded or otherwise secured to the sides of extension 28. Plates 36 extend from adjacent bushing 30 (i. e. from the pivot or anchor of the shoe) past the end of the broadened portion of band 10 (which broadened portion forms the friction face of the shoe), thus bridging across the point midway between the anchor and the end of the friction face, which is the point of maximum buckling strain.

While one illustrative embodiment has been described in detail, it is not my intention to limit the scope of the invention to that particular embodiment, or otherwise than by the terms of the appended claims.

I claim:

1. A brake shoe having an outer cylindrical band providing the friction face of the shoe, and a stiffening web projecting inward-

ly from said band and extending at one end of the shoe as an integral pivot arm, in combination with a separate reinforcing member secured along the side of said arm beyond 5 the end of the friction face, and serving to reinforce the web against buckling immediately beyond the end of the friction face, where the braking pressure is a maximum, without substantially adding to the weight 10 and cost of the shoe.

2. A brake shoe having an outer cylindrical band providing the friction face of the shoe, and a separate stiffening web secured along its outer edge to the inner face of the 15 band and projecting inwardly from said band and extending at one end of the shoe as an integral pivot arm, in combination with a separate reinforcing member secured along the side of said arm beyond the end 20 of the friction face, and serving to reinforce the web against buckling immediately beyond the end of the friction face, where the braking pressure is a maximum, without substantially adding to the weight and cost of the 25 shoe.

3. A brake shoe having an outer cylindrical band providing the friction face of the shoe, and a stiffening web projecting inwardly from said band and extending at 30 one end of the shoe as an integral pivot arm, in combination with separate reinforcing members secured along the opposite sides of said arm, and serving to reinforce the web against buckling immediately beyond the 35 end of the friction face, where the braking pressure is a maximum, without substantially adding to the weight and cost of the shoe.

4. A brake shoe having an outer arcuate band, a stiffening web secured to the inner 40 face of the band and continued integrally at one end of the shoe to form a projecting arm, a reinforcing plate secured to the side face of said arm, and an integral narrowed ex-

tension of said band secured to and reinforcing the outer edge of said arm. 45

5. A brake shoe having an outer arcuate band, a stiffening web secured to the inner face of the band and continued integrally at one end of the shoe to form a projecting arm, a reinforcing plate secured to the side face of said arm, and an integral narrowed extension of said band secured to and reinforcing the outer edge of said arm, said narrowed extension having one or a pair of side wings engaging one or both sides of 55 said arm.

6. A brake shoe having an outer band, at least part of which forms a cylindrically-curved friction face for the shoe, in combination with a stiffening web extending beyond the end of said face as a projecting arm, and a separate reinforcement for said web and arm which crosses from one side to the other of said end of the friction face, and serving to reinforce the web against 60 buckling immediately beyond the end of the friction face, where the braking pressure is a maximum, without substantially adding to the weight and cost of the shoe. 65

7. A brake shoe having an outer band, at 70 least part of which forms a cylindrically-curved friction face for the shoe, in combination with a stiffening web extending beyond the end of said face as a projecting arm, and separate reinforcements for opposite sides of said web and arm which cross from one side to the other of said end of the friction face, and serving to reinforce the web against buckling immediately beyond the end of the friction face, where the braking pressure is a maximum, without substantially adding to the weight and cost of the shoe. 75

In testimony whereof, I have hereunto signed my name.

VINCENT BENDIX.
